UNITED STATES PATENT OFFICE.

EDWARD H. WUEST, OF CINCINNATI, OHIO.

HAND-BAG.

1,104,463.

Specification of Letters Patent. Patented July 21, 1914.

Application filed October 9, 1912. Serial No. 724,789.

To all whom it may concern:

Be it known that I, EDWARD H. WUEST, a citizen of the United States, residing at Cincinnati, in the county of Hamilton and State of Ohio, have invented certain new and useful Improvements in Hand-Bags, of which the following is a specification.

My invention relates to improvements in hand bags to be used as school bags or shop bags.

One of its objects is to provide a bag capable of being folded to accommodate large or small articles as required.

Another object is to provide an improved manner of folding and securing the bag in folded position.

Another object is to provide an extensible handle to serve either as a shoulder strap or support for the bag or as a short multiple strand handle.

My invention also comprises certain details of form, combination and arrangement, all of which will be fully set forth in the description of the accompanying drawings in which:

Figure 1 is a front elevation of my improved bag in the unfolded position with flap closed, and short handle. Fig. 2 is a front elevation with the flap lifted and handle extended. Fig. 3 is a vertical section on line $v-v$ of Fig. 2. Fig. 4 is a rear elevation of Fig. 1. Fig. 5 is a front elevation of the bag in folded position with the flap closed. Fig. 6 is a view similar to Fig. 2 illustrating a modification. Fig. 7 is a front elevation of the modification of Fig. 6 in folded position.

The accompanying drawings represent the preferred embodiments of my invention.

As illustrated in Figs. 1 to 5, A represents the body of a bag preferably of rectangular outline. B represents a flap to fold over and close the bag opening, and is preferably formed integral with the body of the bag. An inside pocket 2 is preferably formed near the mouth of the bag to separately hold smaller articles. 2' represents a line of stitches at the bottom of pocket 2. In the unfolded position Figs. 1, 2, 3, and 4 the bag is in position to hold large objects, and to be filled to its full capacity.

Where only small books or light articles are to be carried or the bag is to be carried empty, the bag is preferably folded horizontally on line 3 near its middle and the two lower corners 4 and 5 folded inwardly

on lines 6 and 7, and the lower edge of the bag attached to one side of the bag near its mouth. In order to attach the various parts of the bag together where desired, various connecting means may be employed. I preferably employ ball and socket connecting members such as commonly employed on gloves and carriage curtains, one member comprising a ball with means to permanently attach it to the goods, and the other comprising a hollow button or socket with means to attach it to the goods. In order to attach the folded lower end of the bag to the upper portion, I provide a ball member 8 near the mouth of the bag and a socket member 9 at the lower end of the bag to engage member 8. The lower end of the bag also carries a ball member 10 to be engaged by a socket member 11 carried centrally by the flap, thereby securing a double and central connection to hold the folded end of the bag in position. The flap overlaps the folded end of the bag and carries two socket members 12 to engage ball members 14 near the mouth of the bag. As illustrated in Fig. 1, the flap is held in place by members 12 and 14 while as illustrated in Fig. 5, it is held in place by members 12 and 14 and also by members 10 and 11.

The handle or strap D is permanently attached at opposite ends to the rear face of the bag by means of rivets or connecting members 15, and 16, and is of sufficient length so as to support the bag by resting the strap over the shoulder of the user. The strap is provided with two or more socket connecting members 18, 19, and corresponding ball members 20, 21 which enable the strap to be folded upon itself and the loops secured together to form a short handle of several strands as illustrated in Figs. 1, 4, and 5. The several strands form a hand grip more readily and conveniently grasped than a single strand. In Fig. 2 the strap is shown in extended position to be used as a shoulder strap.

In the modification Figs. 6 and 7, the bag A' designed to be folded horizontally upon the line 30 and the lower edge of the bag is provided with socket members 31, to engage ball members 32 near the mouth of the bag, while the flap is provided with socket members 34 to engage either the ball members 32 or ball members 36, carried by the lower end of the bag.

The article herein illustrated and de-

scribed is capable of considerable modification without departing from the principle of my invention.

Having described my invention what I claim is:

1. A hand-bag of flexible material open at the top and adapted to be folded transversely upon itself, a flap to fold over and cover the bag opening, a fastening member 10 on the front of the bag near the top thereof, a fastening member on the back of the bag near the bottom thereof, and a fastening member on said flap to coöperate with the fastening member on the front of the bag 15 when in unfolded position and with the fastening member on the back of the bag when in folded position.
2. A hand bag of flexible material open at the top and adapted to be folded trans-

versely upon itself, a flap to fold over and 20 cover the bag opening, fastening members near the top and bottom of the front of the bag adapted to coöperate with each other 25 to secure the bag in folded position, fastening members on the back of the bag near the bottom thereof, and fastening members on said flap adapted to coöperate with the fastening members on the front of the bag near the top when the bag is in unfolded 30 position and with the fastening members on the back of the bag when in folded position.

In testimony whereof I have affixed my signature in presence of two witnesses.

EDWARD H. WUEST.
